UNITED STATES PATENT OFFICE.

CHARLES ADOLPH MAHN, OF NEW YORK, N. Y.

DELIVERY-SPOUT FOR CANS.

1,124,495.

Specification of Letters Patent. Patented Jan. 12, 1915.

Application filed August 20, 1913. Serial No. 785,724.

To all whom it may concern:

Be it known that I, CHARLES A. MAHN, a citizen of the United States, residing at 320 East Ninety-fourth street, New York, in the 5 county of New York and State of New York, have invented certain new and useful Improvements in Delivery-Spouts for Cans; and I do hereby declare the following to be a full, clear, and exact description of the invention, such as will enable others skilled in the art to which it appertains to make and use the same.

This invention relates to delivery spouts for vessels, and more particularly to a delivery spout to be used with cans containing condensed milk.

One of the principal objects of my invention is to provide a spout for use with cans having a plug closure, the plug adapted to 20 be used as a closure for the spout when the same is in position.

Another object is to provide a sanitary delivery means for cans of condensed milk or other fluids, and one which will prevent 25 undue waste of the fluid through leakage.

A further object is to provide a device of the class described which will be simple, durable, efficient in operation and inexpensive to manufacture.

With these and other objects in view, the 30 invention consists in the construction, combination, and arrangement of parts herein-after more fully described and claimed, and illustrated in the accompanying drawing, in 35 which like characters of reference indicate like parts throughout the several views, and in which,

Figure 1, represents a perspective view of a can having the plug removed therefrom 40 and showing the spout ready to be placed in position. Fig. 2, represents a perspective view showing my invention in operation. Fig. 3, represents a perspective view showing the invention as applied to a can, the 45 spout being closed. Fig. 4, represents a vertical sectional view through a portion of a can, my invention being applied thereto.

Referring more particularly to the drawing, 5 represents a can containing condensed 50 milk, said can having one end formed with

an opening 6, therein, said opening being closed when the can is filled at the factory, by a plug 7. It will be understood that the can forms no part of my invention, being shown merely to illustrate the type of can in 55 connection with which my invention is primarily intended to be used.

The spout comprises a hollow tube 8, slightly conical shaped, the lower end being 60 slightly less in diameter than the upper end, and said lower end is flared inwardly and is adapted to fit into the opening 6 in the can 5. A collar 9, surrounds the tube near the lower end and is adapted to engage the end of the can to limit the inward movement of the 65 tube, and to prevent leakage of the contents of the can around the tube. The outer surface of the tube below the collar 9, is adapted to fit against the conical flange 10, formed at the opening in the top, as is usual in this 70 type of can. The plug which closes the opening in the can, is formed of a disk of metal stamped to form a body portion 11, to fit in the flange 10, and a flange portion 12, adapted to bear against the end of the can. 75

In using the spout, the plug is removed from the can and the spout inserted in its place. When this is done the plug is inserted in the upper end of the spout as shown in Figs. 3 and 4, the upper end of the 80 tube being made of a slightly greater diameter than the lower end thereof so that the plug will snugly fit said tube. By this arrangement it is evident that the contents of the can will be protected from flies and other 85 insects which might deposit germs therein, and that a very sanitary spout is provided. It will of course be understood that when the contents of the can are to be poured out, the plug will be removed from the spout to 90 be replaced when the can is not in use.

Having thus fully described my invention, what I claim as new and desire to secure by Letters Patent, is,

In combination, a can having a centrally 95 disposed opening surrounded by an inturned conically disposed flange, a conical tubular spout member having an external annular flange, said member adapted to be removably inserted into said opening, the restrict- 100

ed end inward, until said flange of said member rests against the outer surface of the can and the conical body of the member snugly seats in the conically disposed flange surrounding said can opening, and a cap adapted to be removably seated in either said opening or the enlarged end of said spout member.

In testimony whereof I have signed my name to this specification in the presence of 10 two subscribing witnesses.

CHARLES ADOLPH MAHN.
